UNITED STATES PATENT OFFICE

RALPH APICHELL, OF NORTH OLMSTEAD, OHIO, ASSIGNOR OF ONE-HALF TO CHARLES SPERO, OF CLEVELAND, OHIO

DESIGN FOR A TOY ANIMAL

Application filed November 27, 1931. Serial No. 41,885. Term of patent 3½ years.

To all whom it may concern:

Be it known that I, RALPH APICHELL, a citizen of the United States, residing at Stop 21, Lorain Road, North Olmstead, Cuyahoga County, Ohio, have invented a new, original and ornamental Design for a Toy Animal, of which the following is a specification, reference being had to the accompanying drawing, forming part thereof:

Fig. 1 is a perspective view and Figs. 2 and 3 are front and side elevations respectively of an embodiment of the invention, wherein shaded areas represent colors contrasting with the unshaded areas.

I claim:

The ornamental design for a toy animal, as shown and described.

RALPH APICHELL.
